FREDERIC C. WILLIAMS, OF CHICAGO, ILLINOIS, ASSIGNOR TO E. GOLDMAN & CO., INC., OF CHICAGO, ILLINOIS, A CORPORATION OF ILLINOIS.

BEST AVAILABLE COPY   LABELING-MACHINE.

No. 896,675.

Specification of Letters Patent.   Patented Aug. 18, 1908.

Application filed January 27, 1908.   Serial No. 412,839.

To all whom it may concern:

Be it known that I, FREDERIC C. WILLIAMS, a citizen of the United States, residing at Chicago, in the county of Cook and State 5 of Illinois, have invented a new and useful Improvement in Labeling-Machines, of which the following is a specification.

This invention relates to an improvement in labeling machines particularly adapted 10 for applying labels to bottles, though it may be used or adapted for labeling other articles; and it has for its objects to provide a simple construction of machine capable of rapid action, and in which the labels are applied 15 firmly, accurately and smoothly to the bottles or other articles.

In the drawings, Figure 1 shows the machine by a view in front elevation with the parts in normal or non-operating position; Fig. 2 is a view of the same in side elevation; Fig. 3 is a section on line A, Fig. 1; Fig. 4 is an enlarged broken view, showing the mechanism of the head or upper part of the machine with the parts represented as they appear when the pickers are about to take labels from their magazines; Fig. 4¹ is a similar view, with the parts represented as they appear when the pickers are applying labels to a bottle; Fig. 4² is a similar view with the parts represented as they appear after the pickers have placed the labels and while the wipers are applying them about the bottle; Fig. 4³ is a similar view with the parts represented as they appear after the wipers have completed their operations; Fig. 5 is a top plan view of the machine; Fig. 6 is a section on line B—B, Fig. 4 or Fig. 4³, with the parts in the position they are shown to occupy in the last-named figure; Fig. 7 is a broken section on line D, Fig. 4; Fig. 8 is a section on line E, Fig. 7, and Fig. 9, a section on line F, Fig. 7; Figs. 10 and 11 are enlarged, broken views both taken on line G, Fig. 6, but respectively showing a label-wiper for the body 45 of the bottle and its cooperating picker in opposite extreme positions; Fig. 12 is an enlarged broken section on line H, Fig. 3; Fig. 13 is a view in elevation of the spirally-grooved plunger of Fig. 12; Fig. 14 is an enlarged section on line I, Fig. 12; Fig. 15 is an enlarged section on line J, Fig. 1; Fig. 16 is an enlarged section through the mechanism of the bottle-neck label-wiper on line K, Fig. 6; Figs. 17 to 22, inclusive, are end views of different forms, additional to the form repre-

sented in preceding figures, of rollers suitable for use as the heads of the bottle-neck label-wipers, and Figs. 17^a to 22^a, inclusive, are plan views of the same, respectively; Fig. 23 is a broken section enlarged over the representation thereof in Fig. 3, of the dating and stamping mechanisms for the labels that are applied about the body of the bottle; Fig. 24 is a similar view of the same, showing said mechanisms in the act of performing their different functions, and Fig. 25 is a section on line L, Fig. 23; Figs. 26 and 27 are similar broken views in rear elevation of the stationary frame for actuating the wiper and picker-mechanisms and showing the actuating parts which engage with the frame in two successive positions; Figs. 28 to 31, inclusive, show, each, only one of the two similar side-bars of said frame with the aforesaid actuating parts in further successive positions; Fig. 32 is a detail plan view of clutch-mechanism co-operating with a follower-plate, the purpose of which will hereafter appear; Fig. 33 is a broken sectional elevation on line M, Fig. 32; Fig. 34 is a broken sectional elevation on line N, Fig. 26; Fig. 35 is a transverse sectional view on line O, Fig. 3; Fig. 36 is a sectional view also on line N, Fig. 26; Fig. 37 is a broken plan view of the parts shown in Fig. 36; Fig. 38 is a sectional elevation on line P, Fig. 37, and Fig. 39 is a broken perspective view of a magazine-bar and its support.

The base 32 with a hollow standard 33 rising from its rear end are represented as an integral casting, the base having formed upon it a housing 34 extending centrally along its upper side from the front of the standard, adjacent to which there rises from the housing an extension forming a bearing 35; and from the rear side of the standard, near the base, extends inwardly a bearing 36 (Fig. 3), above which is the outwardly extending bearing 37. The drive-shaft 38 is journaled in the bearings 36 and 35 and carries, loosely mounted on its outer end, a belt-pulley 39 and adjacent to the latter a gear-wheel 40 meshing with a similar wheel 41 on the outer end of a shaft 42 journaled in the bearing 37 and carrying on its inner end, within the standard, a sprocket 43, having a chain-connection 44 with a similar sprocket 45 on a shaft 46 journaled in bearings in the upper part of the standard to extend across the same and performing the stirring-function on the font for containing the paste or

other adhesive substance for the labels hereinafter described.

Inside the standard the shaft 38 carries a cam 47 into the path of which extends an anti-friction roller 48 projecting from a vertical rod 49 having its lower end bifurcated to straddle a collar on the shaft 38. This rod is confined to reciprocate longitudinally in bearings 50 and 51 on the inner wall of the standard, and passes through the top of the latter; and a spiral spring 52 is confined about it between the bearing 51 and adjustable nuts 53 to be set by raising the rod, for the purpose hereinafter described, under the action of the cam 47 and lowering it when the cam clears the roller 48. Toward the upper end of the rod it carries, in the standard, a sleeve 54 against the lower end of which is confined, by nuts 55 on the rod, a spiral spring 56 surrounding the latter, the sleeve terminating at its upper end in a pair of circumferential collars forming a recess 57, and being confined by a collar 58 pinned to the rod. A bell-crank 59, fulcrumed at 60, has one arm engaging with the recess 57 and its other arm connected by a link 61 with a horizontally reciprocable plunger-rod 62 for working the dating-device and the rear label-clamp as hereinafter described. The purpose of providing the spring-pressed sleeve 54 is to render the action of the rod on the bell-crank yielding, so that if any obstruction occurs in the working of the aforesaid dater and clamp there will be sufficient yield, notwithstanding the rigidity of the rod, to avoid injury to the mechanism. For a similar purpose a spiral-spring 63 is confined about the upper projecting end of the rod against a circumferentially recessed head 64 engaged by one end of a lever 65 fulcrumed between its ends to a support 66 and provided in its opposite end with an elongated slot 67 at which is pivotally connected with it the plunger-rod of the forward label-clamp, hereinafter described.

On the forward end of the shaft 38 is secured a crank-disk 68, behind which the upper part of the bearing 35 is extended as a loop-like casting 69 terminating at its upper end in a head 70 at which it is bolted to the face of the standard 33; and this casting carries the parallel vertical guides 71, 71 for a vertically reciprocating cross-head 72 having a pitman-connection 73 with the wrist-pin 74 of the disk 68.

A dash-pot 75, of ordinary construction, has its piston-rod 76 connected with a lip 77 projecting forwardly from the cross-head, the dash-pot serving as a check to the downward movement of the cross-head against the tendency of the weight of the mechanism carried by it to unduly accelerate such movement.

On the forward end of the top of the head 70 are provided parallel horizontal guides 78

(Fig. 1), for receiving the feet which project outwardly from legs 79 depending from the base of a paste or glue-font 80, of the preferred general shape illustrated. Centrally in the ends of this font is journaled a paste-working roller 81 having its rear journal extended to carry a sleeve 82, pinned to it, and formed with an angular socket to receive the squared forward end of the shaft 46 (Fig. 7). Thus, as will be seen, rotation of the drive-shaft, through its sprocket and chain-connection with the shaft 46, constantly rotates the roller 81 in the font, in which a scraper 83 is shown in Fig. 8 to bear against the roller. The ends of the font are shown to be extended upwardly (Figs. 8, 9), to afford seats for the ends of a cover 84, which is removably fastened in place and affords a shield; and the top of the font is open except for this sheet-metal shield. Ears 85 extend from the font ends at their opposite sides, the pairs of ears on each side affording bearings for rollers 86 carrying crank-arms 87 connected by springs 88 with the font-ends and affording at their free ends bearings 89 for rollers 89. The springs tend to hold the rollers 89 in contact with the surface of the roller 81 and are spaced from the rollers 86 for the purpose hereinafter explained. Each roller 86 and 89 may consist of a continuous rod carrying rotatably upon it a rubber roller which is preferably divided between its ends, as indicated at 90 in Fig. 7, to form it in two independent sections. As will be observed, the font may be readily removed at the forward end of the machine by withdrawing it lengthwise, as for cleaning and replenishing it, and the like, and it may be as readily replaced.

A shelf 91 extends from the face of the standard lengthwise and centrally over the font. It comprises a head 92 containing vertical slots 93, near its edges, through which it is bolted to the standard in a manner to render it vertically adjustable to adapt the machine for labeling bottles of varying diameters and shapes; from the face of the head extend parallel ears 94 between which is adjustably fastened the shelf-proper having a concave upper surface to adapt it to afford a bed for a bottle while being labeled, the forward end of the shelf being curved downwardly to afford a lip 95 serving to guide the bottle in placing it in position to be labeled; and at the rear end of the shelf rises a bearing 96 for a set-screw 97 carrying a disk 98 affording an abutment for the bottom of the bottle, this abutment being thus adjustable to adapt the shelf to bottles of different lengths.

A neck 99 extends forwardly and upwardly from the top of the standard 33, and is the part from which rises the support 66 having fulcrumed upon it the lever 65 (Fig. 3). This neck is formed on a rectangular frame 100 composing the top-section of the ma-

chine-frame and has longitudinal ledges 101 on its opposite inner sides for adjustably seating upon them a rear rectangular supplemental frame 102, open at its forward end, and a forward smaller frame 103, of general rectangular shape (Fig. 5).

Between the sides of the frame 103, near its forward end, extends a rod 104, and depending from the sides of this frame are ears 105 forming bearings for the ends of a rotary shaft 106 provided at opposite sides of its transverse center with right and left screw-threads (Fig. 1); and on one end of this shaft is provided a knurled collar 107 for turning it.

15 Hung on the rod 104, at suitable distances apart, are similar bars 108, 108, each having an upper section 108¹ extending at a right-angle from it at which it is hung on the rod, and a lower section 108² extending parallel 20 with said upper section and terminating in a nut 109 at which it surrounds a threaded part of the shaft 106, whereby turning the latter at the collar 107 will bring the bars 108 closer together or spread them further apart, 25 depending on the direction of turning. Each of these bars has a downward extension 110 terminating at its lower end in an inwardly projecting finger 111.

Rigidly depending from the center of the 30 back of the frame 103 is an arm 112 (Fig. 3), terminating at its lower end in a forwardly projecting finger 113 in the plane of the fingers 111, and a similar arm 114 faces the arm 112 and terminates at its lower end in a back wardly projecting finger 115 in the plane of 35 the finger 113. This last-named arm is supported on a stud 116 extending backwardly from and reciprocably movable in the forward side of the supplemental frame 103, 40 from which there also depends a bearing 117 for a set-screw 118 working in a nut 119 projecting forwardly from the face of the arm 114, whereby the latter may be moved back and forth relative to the arm 112 by turning 45 the set-screw. These depending arms form a magazine for a pile of labels 120 (Fig. 4) to be applied to the necks of bottles, the fingers on the ends of the arms affording a seat for the pile; and the described adjustment provided for the arms enables the magazine to be expanded and contracted for adapting it for labels of different dimensions, as for bottles of different sizes. Moreover, the supplemental frame 103 is adjustable lengthwise 50 of the frame 100 for placing the said magazine relative to different lengths of bottle-necks, this adjustment being effected through movement of the supplemental frame by hand on loosening thumb-screws 121 working 55 against its sides through the sides of the frame 100.

A follower-plate 122 rests on the top of the label pile 120 and bearing upon the plate is a yoke 123 pivotally supported on one end of 60 a lever 124 having its ends bent at right-

angles to the body of the lever in opposite directions, the other end being pivotally supported in the slot of a bracket 125 terminating in a head 126 containing a vertical opening to fit slidingly on a vertical post 127 of 70 T-shape in cross-section secured to the back of the supplemental frame 103 at a recess therein. The sliding movement of the head 126 on its vertical guide-post enables it to follow the diminishing pile 120 as labels are 75 picked from its bottom, as hereinafter described, and any tendency of the pickers to lift the pile in operating against its under side, and thereby disorganize it, is resisted by the consequent turning of the lever 124 80 and binding or clutching its upper bent end frictionally against the face of the post 127. The rear supplemental frame 102 is likewise adjustable upon its seat on the ledges 101 of the frame 100, upon loosening thumb-screws 85 128 working against its sides through the sides of the main frame and turning similar screws 129 which work against the rear end of the frame 102 through the corresponding end of the frame 100. These last-named screws serve, by turning them in one direction, to move the rear supplemental frame forward, and it may be moved backward by hand, this adjustment being provided to position the magazine, hereinafter described, 90 holding the pile of labels for the bodies of bottles, relative to the latter. This last-named magazine is similar to that for the neck-labels 120 and involves the following-described construction:

Extending between the sides of the frame 102, near its rear end, is a rod 130, and below the latter is a shaft 131 provided with right and left threads, in all respects like the shaft 106, and journaled in depending ears 132; and on this rod and shaft are adjustably supported similar depending bars 133 in all respects like, or substantially like, the bars 108, and like the latter terminating in inwardly projecting fingers.

Adjacent to a side of the frame 102 there extends, between its rear and forward rails, a rigid rod 134 (Fig. 35), like the rod 131, and directly above the latter extends the shaft 135 journaled in ears 136 on the frame 102, 100 this shaft having right and left screw-threads to work in nuts 137 on the ends of similar bars 138 terminating at their lower ends in fingers, these bars being suspended on the rod 134 and shaft 135 in all respects the same 105 as the bars 108 on their supporting rod and threaded shaft, and being like the latter, terminating in inwardly projecting fingers which 110 co-operate with those on the bars 133 to form a seat for a pile of labels 139 (Fig. 5), confined in the magazine formed by the arms. A follower-plate 140 rests on the pile 139, 115 and upward displacement of this pile, as and for the purpose described in connection with the pile 120, is resisted by the lever-device 120 125 130

represented at 141, like and operating like that described in connection with the pile 120 and being movably supported at its head on a post 142 rising from a corner of the frame 102.

5 Near the junction with the standard 33 of the head 70 there arise from opposite sides of the latter, two similar bent bars 143, 143, coinciding with each other and rigidly fastened 10 at their upper ends to opposite sides of the frame 100 near its rear end. These bars form the frame serving to actuate the label picker and wiper mechanisms, as hereinafter described. The cross-sectional shape of each 15 of these bars is best shown in Fig. 6 to involve, between its upper and lower bent ends, a flat inner bearing-face 144 with a slightly offset face 145 terminating at its lower end, just below the transverse center of the 20 straight section of the bar, in an outwardly deflected end 148 (Figs. 26 and 27). These bars contain in the inner faces of their sections 144 corresponding and coinciding recesses 146, and below the latter similar recesses 147. Coincidentally with the center 25 of each recess 146 a trip-stud 149 projects horizontally from the rear side of the respective bar 143; and a spring-finger 150 is fastened to the inner face of the lower bent section of each bar 143 to extend at its free end 30 into a guide-groove 151 (Fig. 26), provided in the face 144 of said bar just below the recess 147 therein, this spring performing a block-tripping function hereinafter described.

35 On opposite sides of the cross-head 72 are fastened similar arms 152 extending vertically and terminating in yokes 153 forming bearing-heads for the mechanisms which 40 operate with the recessed bars 143 for picking the labels from the bottoms of the magazines and wiping them about the body-portions and necks of bottles 154 successively imposed upon the shelf 91. These mechanisms are 45 duplicates of each other, so that description thereof on one side of the bottle-support will suffice for both, with like reference-characters applied to corresponding parts in the two sets of mechanisms: A rock-shaft 155 is 50 journaled at its ends in bearings provided on the opposite arms of the yoke, this shaft being flattened longitudinally on its normally upper side between the bearings, adjacent to one of which it carries an adjustable stop 156 55 to engage with a stud 157 projecting into its path from a yoke-arm for limiting the throw of the shaft. Fixed upon the shaft in a collar 158 thereon, near the stop 156, and adjustably confined in the collar (Figs. 10 and 60 11) is a picker-finger 159 for the labels 139; and similarly fixed on the same shaft, near its opposite end, is a picker-finger 160 for the labels 120 (Fig. 3). The shaft 155 projects 65 at its rear end beyond its bearing and there carries a crank-arm 161 pinned to the shaft;

70 with a spring 162 (Fig. 6) about the shaft connecting the crank-arm with the adjacent bearing to tend to return the crank-arm to normal position; and the free end of the crank-arm carries an anti-friction roller 163 75 to travel against the frame-bar surface 145. Directly above the shaft 155 is journaled in bearings in the upper ends of the yoke-arms a cylindrical shaft 164 carrying on its rear projecting end a block 165 to travel against the bar-surface 144. Beyond the block the shaft is provided with a circumferential groove 166 (Figs. 36-38) and is there surrounded by a cap 167 containing in the end of the wall of its socket-portion a slot 168 to 80 straddle a stud 169 projecting into it from the adjacent face of the block 165, the cap being confined on the shaft, with slight independent rotary movement determined by the stud 169, by a pin 170 passing transversely through the cap in the groove 166; and a spiral-spring 171 surrounds the cap with one end secured to the block and its other end to a leaf-spring 172 fastened at one end in a diametrical slot in the outer or rear 85 end of the cap, the free end of the leaf-spring extending into the plane of the stud 149 on the frame-arm 143. The block 165 has the two flat bearing-surfaces 165¹ and 165² to 90 travel against the face 144, and adjacent to 95 the corner between these surfaces they are respectively provided with the notches 165³ and 165⁴, toward which the surfaces curve slightly, as represented. A wiper 173 (Fig. 6), for the wider labels 139, is secured on the 100 shaft 164 adjacent to its rear bearing, and consists of a metal collar having jaws between which a wiping flap 174 of flexible material, preferably rubber, is confined to project at its free end into contact with the bottle-body. On the shaft 164 near its forward 105 end is secured the wiper 175 for the bottle-necks, the preferred construction of which is best shown in Fig. 16: A collar 176 is keyed to the shaft and carries, to extend transversely across it, a sleeve 177 with which telescopes a tube 178 closed at its outer end and containing a spiral-spring 179 confined against the inner end of a plunger-rod 180 110 non-rotatably working in the tube and terminating in its outer end in a yoke 181 (Fig. 6), having journaled in it a star-shaped frame 182 between the arms of which are journaled the three similar rollers 183 forming a cluster, composed by preference of rubber sleeves rotatably surrounding rods extending between the star-shaped bearings. Other shapes of the label-wiping heads for the wiper 175, each consisting of a single member, preferably of rubber, are illustrated in Figs. 17 to 120 22, inclusive, by end views and in 17^a to 22^a, inclusive, by plan views. A collar 184, secured about the inner end of the tube 178 is 125 journaled in the free ends of two similar bent arms 185 loosely surrounding at their oppo- 130

site ends the shaft 155 to embrace the collar of the picker 160.

In the up-and-down movement, under the action of the crank-disk 68, of the arms 152 and yokes 153, each of the latter is guided by a shoe 187 (Fig. 4) supported to bear against the outer face of a frame-bar 143 on an ear 188 projecting outwardly from an arm of the respective yoke 153.

10 Immediately above the head-end of the bottle-support there extends from the face of the standard, on which it is vertically adjustable over the bottle-support, a horizontal frame 189 (Figs. 23-25) of substantial 15 U-shape having longitudinal slots 190 and 191, respectively, in its upper and lower sides and having near the forward end of its upper side a spring-controlled shaft 192 journaled in bearings 193 and carrying on 20 its projecting ends corresponding arms 194 in the outer ends of which is journaled an inking-roller 195 for applying ink to the type of the dating-device, hereinafter described. Between the arms of this frame is reciprocably confined a slotted head 196 secured to the forward end of the plunger-rod 62 actuated by the bell-crank 59. In the slot provided in the forward face of this head, and near the upper end thereof, is journaled a 25 bell-crank lever 197, the shorter and upwardly extending rear arm of which projects into the path of an adjustable stop 198 in the forward end of the top of the frame, and on the forward upper end of the longer arm of which is mounted the type-carrying dating-head 199 with the inking-roller, under the action of the spring on the shaft 192, bearing against the type in the normally retracted position of the frame 189. A similar bell-crank 200 is fulcrumed in the head 196 immediately below the bell-crank 190 with its rear downwardly extending shorter arm projecting into the plane of an adjustable stop 201 in a bearing-lug 202 depending from 30 the extreme forward end of the lower side of the frame 189 coincident with the longitudinal slot therein in which said shorter arm works, as the shorter arm of the bell-crank 197 works in the slot 190; and on the 35 forward end of the bell-crank 200 is pivotally carried, to accommodate itself to any angle of the bottle-body, a rubber-faced label-clamping head 203 to hold a label 139 against slipping on the bottle-body while it 40 is being wiped about the same by the wipers 174. The two bell-cranks are normally held together in the position shown in Fig. 23 by spiral-springs 204 connecting them. In the 45 forward stroke of the head 196, the dater is inked by moving it across the inking-roller and is advanced underneath the pile of labels 139 in their magazine, so that when the short arm of the bell-crank 197 encounters the stop 198, the dating-head 199 is 50 raised against the undermost label to date 55

it on its back surface to be applied to the bottle. Thus, of course, the date on the label is not exposed to view when the label is on a bottle, but the user of the machine does not wish it to be so exposed. Similarly, 70 the forward movement of the head 196 causes the shorter arm of the bell-crank 200 to encounter the stop 201 with the result of depressing the clamp 203 against the bottle for the purpose hereinafter described. 75

A clamping-device is also provided for holding a neck-label against slipping while it is being wiped about the bottle-neck by the action of the coöperating wiper-rollers 183, particular reference being had to Figs. 80 12-14: In a bearing 205 provided centrally in the rear rail of the supplemental frame 116 is perpendicularly and rigidly supported a headed tube 206 to coincide at its lower end with the neck of a bottle imposed upon 85 its support. Within this tube is reciprocably confined a head 207 pivotally connected with the lower end of a hanger-bar 208 passing through the slotted cap of the tube and pivotally connected at its upper 90 end with the lever 65 at the longitudinal slot in its forward end, thereby to render the tube 206 adjustable back and forth on the lever to correspond with any adjustment of the frame 116 relative to bottle-necks of 95 different lengths. In the bottom of the head 207 is centrally swiveled at its upper end a cylindrical spindle 209 extending through a bearing 210 in the lower end of the tube, the spindle containing a spiral-groove 211 into which extends, through the wall of the tube and the bearing 210, a pin 212; and the spindle carries on its lower projecting end a rubber-faced clamp 213 surrounded by an upwardly tapering guard 214. 105

The operation is as follows: While the machine may be equipped for operation by hand, it is shown to be equipped for operation by power applied to the belt-wheel 39, the continuous rotation of which uninterruptedly rotates the mixing-roller in the paste-font 80. On the drive-shaft 38, adjacent to the pulley 39, is a clutch-device 215 of ordinary construction for coupling the pulley to the shaft by depressing the forward 110 projecting end of a treadle 216 to depress the rear end of a spring-pressed lever 217 linked at one end to the adjacent end of the treadle and having a connection with the clutch at its opposite end. Thus one depression of the 115 treadle will produce, by a single rotation of the drive-pulley, a complete operation of the machine, which is arrested thereafter by automatic unshipping of the clutch, in the usual manner of such devices. 120

With the parts in position of rest in which they are shown in Fig. 1 and a bottle to be labeled imposed on its support, the first effect of the rotation of the drive-shaft, after depressing the treadle, is to cause the crank- 125 130

disk 68 to raise the cross-head 72 until the horizontally extending pickers, which are supplied with paste on the upper faces of their free ends in the manner hereinafter described, contact with the lowermost labels 120 and 139 in their respective magazines. This brings the parts into the condition represented in Fig. 4. Further turning of the drive-shaft lowers the cross-head to depress the pickers, with the label carried by each pair, until the rear label is applied part way about the body of the bottle and the forward label is similarly applied to the bottle-neck, thus bringing the parts into the condition represented in Fig. 4^a. Meantime the rod 49, in rising, has actuated the bell-crank 59 to advance the dating-device underneath the pile of labels 139 and permit it to date the undermost label and to cause the clamping-head 203 to bear against the deposited rear label, and also to depress the forward end of the lever 65 and thereby turn the clamp 213 from its normal rearwardly projecting position to its forwardly projecting operative position and depress it against the label deposited upon the bottle-neck. Continued turning of the drive-shaft brings the parts into the position represented in Fig. 4^b. In this position of the yokes 153 the crank-arms 161 have cleared the deflected ends 148 of the frame-faces 145, as shown in Fig. 27, permitting the recoil of the springs 162 to turn the picker-shafts 155 to the position shown in Fig. 11, of registering the free ends of the pickers with the spaces between the font-rollers 86 and 89. In this same position of the yokes the leaf-springs 172 have encountered, as shown in Fig. 27, the studs 149 to tension the springs 171. During all of the movement, until the crank-arms 161 have attained the position shown in Fig. 27, the faces 165¹ of the blocks 165 slide against the frame-surfaces 144; and in this position the lower corners of the blocks are about to register with the notches 146 in the frame-bars. Continued rotation of the drive-shaft lowers the yokes 153 to bring the blocks 165 coincident with the recesses 146, where their leaf-springs have cleared the studs 149, thereby permitting their tensioned springs to turn them by entering said corners into said recesses and overturning the blocks to the position represented in Fig. 28, wherein their surfaces 165² ride against the frame-surfaces 144. In this turning of the blocks, they turn with them the shafts 164 to turn the wipers into horizontal position against the labels on the bottle; and the accompanying turning of the shaft 155 has brought the pickers to the aforesaid registering position represented in Fig. 11. This position of the parts is also represented in Fig. 4^b. Further continued rotation of the drive-shaft rides the surfaces 165² of the blocks 165 down the respective sur-

faces of the frame-bars 143 until their corners between the aforesaid notches in the blocks register with the upper ends of the frame-bar recesses 147, such lowering of the blocks, and with them of the shafts on the yokes 153 and mechanisms carried by the shafts, protruding the pair of pickers on each side of the machine between the respectively adjacent font-rollers 86, 89, into the font to dip their ends into the paste; and it furthermore causes the wipers to follow about the respective contours of the bottle, the rear wipers wiping the label about the bottle-body and the forward ones wiping the label about the bottle-neck. This position of the parts is illustrated in Fig. 4^c. Each label was, of course, coated with paste only on the under sides of its end-portions by contact therewith of the end-portions of the pickers in withdrawing the labels from their magazines, but a more extensive application of paste is unnecessary since it is only necessary to gum the labels in place at their end-portions. The pickers, in thus being protruded into the font in downwardly inclined directions, bear against the lower rollers 86 and tilt the crank-arms 87, and the rollers 89 carried by them, outwardly against the resistance of the springs 88, which, as the pickers are withdrawn in the manner herein-after described, return the rollers to their normal positions, wherein the rollers 89 bear against the roller 81 to take paste therefrom. The action of the forward wipers is peculiar: In the turning of the shafts 164 which lowered them against the bottle-neck, the arms 185 (Fig. 16), loose on the shaft 155, turned with the wipers and thereby advanced the sleeves 178 in their bearings 177 toward the bottle-neck; and the resiliently yielding action of the plunger 180 caused the rollers 183 to snugly bear against the bottle-neck in describing its contour, thereby insuring their contact with the label throughout their wiping action against it. The guard 214 prevents the rollers on the ends of the two forward wipers from interfering with each other. The various other constructions of wiper-heads illustrated in Figs. 17 to 22^a, inclusive, which are respectively adapted for use against bottle-necks of different contours, all operate in substantially the same way as that described of the three-roller head. When, in the continued rotation of the drive-shaft, the blocks 165 register at their aforesaid corners with the recesses 147, as represented in Fig. 29, their surfaces 165² begin to ride on the springs 150 and their notches 165⁴ find fulcrums on the lower ends of the recesses 147, to facilitate the initial backward turning of the blocks, and in this position the crank-arm 73 will have just about reached the dead-center position. In further movement of the blocks to the position represented in Fig. 30, their guidance on the springs 150 turns them at their said cor-

ners in the recesses 147 in the direction of presenting their surfaces 165¹ to the frame-bar faces 144, and in so turning, the blocks initially turn the shafts 164 to raise the wipers 5 toward their normal positions. Accompanying this initial movement of the blocks, and with the crank-arm 73 attaining the dead-center, the attendant descending movement of the rod 49 acts upon the bell-crank 10 59 to retract into normal position the dater and rear label-clamp and to raise the forward end of the lever 65 to effect raising and turning out of the way the forward label-clamp to its normal position.

15 It should here be stated that when the forward label-clamp is in its operative position, the upwardly tapering shield forms on its opposite sides abutments or stops between the opposing heads of the adjacent label-wipers 20 to prevent them from coming together in lowering toward the bottle-neck and to guide them to the latter in their clearance of the clamp.

After the wipers have performed their 25 function, and while they are being raised to normal position, the labeled bottle may be withdrawn to be immediately replaced by another bottle to be labeled, the positions of the parts then being such as to present no obstruction to such change of bottles. As the 30 crank-arm 73 passes the dead-center, the cross-head 72 begins to rise, thereby bringing the notches 165³ in the blocks against the upper edges of the recesses 147, which ful- 35 crum the blocks, whereby, in the further rise of the cross-head, they are turned to the position represented in Fig. 31 to ride their surfaces 165¹ against the frame-bar surfaces 144, thus bringing the wipers to their normally 40 raised position; and the continued rise of the cross-head withdraws the pickers from between the font-rolls, enabling the springs controlling the latter to return them to their normal positions. In withdrawing the pick- 45 ers from between the font-rolls the latter remove surplus paste from them by the rubbing of the picker-surfaces against the rollers. Toward the end of the complete rotation of the drive-shaft, the continued rise of 50 the cross-head brings the rollers 163 on the crank-arms 161 into encounter with the deflected lower ends of the frame-bar surfaces 145 to guide the rollers to those surfaces, in 55 attaining which the crank-arms 161 are turned to raise the picker-shaft and raise the pickers to their normal horizontal position, after which the rollers 163 continue to ride against the surfaces 145 until the drive-shaft has completed its rotation, when the parts 60 are restored to normal position represented in Figs. 1 and 2, and the drive-shaft becomes unclutched, requiring the treadle to be again depressed for the next operation of the machine like that described.

65 It will be apparent that the bars 143 con-

trolling the operations of the pickers and wipers are in the nature of cam-bars, and that their contained recesses 146 and 147, as also the offsets 148 and springs 150, are of the nature of cams, so that any forms of cams suitable for performing the functions for these parts are within the purview of my invention.

An important characteristic of my improved machine is that of the initial movement of the pickers being to rise from their normal or rest position, as the initial movement of the machine to encounter the label in its magazine, then to descend, carrying the label across the bottle in its path, and, 75 finally, to rise to their normal position. This greatly simplifies the mechanism, since the pickers are thereby only required to play between upper and lower extreme positions defined by the label-magazine and the paste- 80 font.

While the machine is shown and described as involving picker and wiper mechanisms for providing labels both on the bodies and necks of bottles, there is no limitation to both 90 intended.

What I claim as new, and desire to secure by Letters Patent, is—

1. In a labeling-machine, the combination of a label-magazine and a paste-font with a 95 bottle-support in the path between them, label-pickers supported to extend at their free ends normally at a distance below the lower delivery-end of the magazine, and mechanism operating to first raise the pickers against the lowermost label, then lower them to carry the label across the bottle 100 its path and then introduce them into said font and finally raise them to normal position.

2. In a labeling-machine, the combination 105 of a label-magazine and a paste-font with a bottle-support in the path between them, label-pickers supported to extend at their free ends normally at a distance below the lower delivery-end of the magazine, mech- 110 anism operating to first raise the pickers against the lowermost label, then lower them to carry the label across the bottle in its path and then introduce them into said font and finally raise them to normal posi- 115 tion, and wipers movably supported to extend across said path and coöperating with said pickers.

3. In combination with a supporting frame, a bottle-support, a bottom-delivery 120 label-magazine and a paste-font respectively above and below said support, a cam-frame, a reciprocating cross-head with means for reciprocating it and provided with arms on opposite sides of the machine, and label- 125 pickers and wipers carried by said arms and having operating connections with said cam-frame, for the purpose set forth.

4. In combination with a supporting-frame, a bottle-support and a bottom-de- 130

livery label-magazine and a paste-font respectively above and below said support, a cam-frame, a reciprocating cross-head with means for reciprocating it and provided 5 with arms on opposite sides of the machine, label-pickers carried by said arms to extend at their free ends normally at a distance below the bottom of the magazine to be first raised against the lowermost bottle-label, 10 then lowered to carry the label across the bottle in its path and dipped into the paste-font and finally raised to normal position, wipers carried by said arms to extend across said path, and connections between the pickers and wipers and said cam-frame for actuating them in their reciprocating movements.

5. In combination with a supporting-frame, a bottle-support and a bottom-delivery label-magazine, and a paste-font respectively above and below said support, a reciprocating cross-head with means for reciprocating it and provided with arms on opposite sides of the machine terminating in bearing-heads, a frame consisting of bars rising at opposite sides of said supporting frame and provided with inner bearing-faces having outwardly deflected lower ends, rock-shafts journaled in said heads and carrying spring-pressed crank-arms engaging said bearing-faces, and picker-fingers extending from said shafts into the path between said magazine and font, for the purpose set forth.

6. In combination with a supporting-frame, a bottle-support, a reciprocating cross-head with means for reciprocating it and provided with arms on opposite sides of the frame terminating in bearing-heads, a frame consisting of bars rising on opposite sides of said supporting-frame and provided 35 with inner bearing-faces containing upper and lower recesses with fingers extending at their free ends against said faces adjacent to said lower recesses, shafts journaled in said heads, wipers on said shafts, and spring-pressed blocks on said shafts riding against 40 said faces, for the purpose set forth.

7. In combination with a supporting-frame, a bottle-support, a reciprocating cross-head with means for reciprocating it and 50 provided with arms on opposite sides of the frame terminating in bearing-heads, a frame consisting of bars rising on opposite sides of said supporting-frame and provided with inner bearing-faces containing upper and 55 lower recesses with fingers extending at their free ends against said faces below the lower recesses therein, shafts journaled in said heads, wipers on said shafts, and spring-pressed blocks on said shafts each having 60 two faces on adjacent sides adapted to ride against said bar-faces and containing notches, for the purpose set forth.

8. In combination with a supporting-frame, a bottle-support, a reciprocating cross-head with means for reciprocating it and 65 provided with arms on opposite sides of the

frame terminating in bearing-heads, a frame consisting of bars rising on opposite sides of said supporting frame and provided with inner bearing faces containing upper 70 and lower recesses with fingers extending at their free ends against said faces below the lower recesses therein, shafts journaled in said heads, wipers on said shafts, blocks on said shafts, each having two faces on adjacent sides adapted to ride against said bar-faces and containing notches, caps on corresponding ends of said shafts having spring-connections with said blocks, leaf-springs extending from said caps, and studs projecting 80 from said bars into the paths of said leaf-springs, for the purpose set forth.

9. In a labeling-machine, the combination with a reciprocating support, of a bottle-neck wiper rotatably carried on said support and having a longitudinally reciprocating stem and a roller on the end of the stem for engaging a bottle-neck.

10. In a labeling-machine, the combination with a reciprocating support, of a bottle-neck wiper rotatably carried on said support and having a longitudinally reciprocating stem, and a roller on the end of the stem for engaging a bottle-neck.

11. In a labeling-machine, the combination with a reciprocating support, of a bottle-neck wiper rotatably carried on said support and having a longitudinally reciprocating stem terminating in a bearing-head, and a cluster of rollers journaled in said head for 100 engaging a bottle-neck.

12. In a labeling-machine, the combination with a reciprocating support, of a bottle-neck wiper rotatably carried on said support and having a longitudinally reciprocating stem terminating in a bearing-head, and a cluster of rollers comprising a star-shaped carrier journaled in said head with three rollers journaled in it for engaging a bottle-neck.

13. In a labeling-machine, the combination with a reciprocating support, of a bottle-neck wiper rotatably carried on said support and consisting of a collar having a sleeve extending transversely thereof, a tube reciprocably supported in said sleeve, a spring confined in said tube, a stem reciprocably confined in the tube against the spring therein, and a roller on the outer end of the stem to engage a bottle-neck.

14. In combination with a supporting-frame, a bottle-support, a reciprocating cross-head with means for reciprocating it and provided with arms on opposite sides of the frame and terminating in bearing-heads, forward and rear bottom-delivery label-magazines above the plane of said support, a paste-font below said plane, a cam-frame, lower rock-shafts journaled in said bearing-heads and carrying forward and rear picker-

- 5 fingers and loosely adjacent to the forward picker-fingers bent arms, upper rock-shafts journaled in said bearing-heads and carrying forward wipers and rear wipers, each forward wiper consisting of a collar on said upper shaft having a transverse sleeve, a tube reciprocably supported in said sleeve and containing a spring, and a stem reciprocably confined in said sleeve against the spring 70 therein and carrying on its outer end a neck-label roller, and a yoke journaled in the ends of said bent arms and surrounding said sleeve, and operating connections between said shafts and said cam-frame, for the purpose set forth.
- 10 15. In a labeling-machine, the combination with a supporting frame for the mechanism including a drive-shaft, of a paste-font on a support in said frame and bodily withdrawable from said support, a mixing-roller journaled in said font, a shaft journaled in said frame having a separable coupling at one end with the adjacent end of said roller, and a driving-connection between said shaft 80 and drive-shaft, whereby withdrawal from its support of said font uncouples said coupling, for the purpose set forth.
- 20 25. In a labeling-machine, the combination with a supporting-frame, of a bottle-support, a label-magazine above said support, a paste-font below said support and containing a mixing-roller, rollers journaled on opposite sides of the font and each carrying arms on its ends with a roller journaled in the free 85 ends of the arms to form therein a pair and bear against the stirring-roller, springs connecting said arms with the font to hold said arm-carried rollers resiliently in contact with said stirring-roller, and a reciprocating cross-head carrying oscillatory picker-fingers to play between said magazine and font and enter the latter between said pairs of rollers.
- 30 35. In a labeling-machine, the combination with a supporting-frame, of a drive-shaft, a bottle-support, a vertically reciprocating rod actuated by the drive-shaft, a horizontally reciprocating plunger-rod supported in the frame and connected with said vertical rod to be actuated by it, label-wipers, and a 90 label-clamp device on said plunger-rod extending over the rear part of said bottle-support and coöperating with said wipers.
- 40 45. In a labeling-machine, the combination with a supporting-frame, of a drive-shaft, a bottle-support, a vertically reciprocating rod actuated by the drive-shaft, a horizontally reciprocating plunger-rod supported in the frame and connected with said vertical rod to be actuated by it, label-wipers, and a label-clamp device comprising a slotted head on said plunger-rod provided with a stop, a 95 bell-crank fulcrumed on said head with one arm extending into the plane of said stop, and a clamping-head on the other arm of the bell-crank coöperating with said wipers.
- 50 55. In a labeling-machine, the combination with a supporting-frame, of a drive-shaft, a bottle-support, a vertically reciprocating rod actuated by the drive-shaft, a horizontally reciprocating plunger-rod supported in the frame and connected with said vertical rod to be actuated by it, label-wipers, and a label-clamp device on said plunger-rod extending over the rear part of said bottle-support and coöperating with said wipers.
- 60 65. In a labeling-machine, the combination with a supporting-frame, of a drive-shaft, a bottle-support, a vertically reciprocating rod actuated by the drive-shaft, a horizontally reciprocating plunger-rod supported in the frame and having a bell-crank connection with said vertical rod for actuating the plunger-rod, label-wipers, and a label-clamp device on said plunger-rod extending over the rear part of said bottle-support and coöperating with said wipers.
- 70 75. In a labeling-machine, the combination with a supporting-frame, of a drive-shaft, a bottle-support, a vertically reciprocating rod actuated by the drive-shaft, a spring-supported sleeve on said rod, a horizontally reciprocating plunger-rod supported in the frame and connected with said sleeve to be actuated by said vertical rod, label-wipers, and a label-clamp device on said plunger-rod extending over the rear part of said bottle-support and coöperating with said wipers.
- 80 85. In a labeling-machine, the combination with a supporting-frame having an upright hollow standard, of a drive-shaft, a bottle-support, a vertically reciprocating rod working in said standard and engaging with the drive-shaft to be actuated by it, a spring-supported sleeve on said rod, a bell-crank fulcrumed in said standard and having one arm in engagement with said sleeve, a horizontally reciprocating plunger-rod supported 90 in the standard and connected at its rear end with the other arm of the bell-crank, label-wipers, and a label-clamp device on the forward end of said plunger-rod extending over the rear part of said bottle-support and coöperating with said wipers.
- 90 95. In a labeling-machine, the combination with a supporting-frame, of a drive-shaft, a bottle-support, a vertically reciprocating rod actuated by the drive-shaft, a horizontally reciprocating plunger-rod supported in the frame and connected with said vertical rod to be actuated by it, label-wipers, and a label-clamp device comprising a slotted head on said plunger-rod provided with a stop, a bell-crank fulcrumed on said head with one arm extending into the plane of said stop, and a clamping-head on the other arm of the bell-crank coöperating with said wipers.
- 100 105. In a labeling-machine, the combination with a supporting-frame, of a drive-shaft, a bottle-support, a vertically reciprocating rod actuated by the drive-shaft, a horizontally reciprocating plunger-rod supported in the frame and connected with said vertical rod to be actuated by it, label-wipers, and a label-clamp and a dater device comprising a slotted head on said plunger-rod provided with upper and lower stops, a bell-crank fulcrumed on said head with one arm extending 110 into the plane of said lower stop and a clamping-head on the other arm coöperating with said wipers, a second bell-crank fulcrumed on said head with one arm extending into the plane of the other stop and a dater on the other arm, and a spring-connection between said bell-cranks tending to return the bell-cranks to normal position.
- 110 115. In a labeling-machine, the combination with a supporting-frame having a top-section, of a drive-shaft, a bottle-support, label-wipers, and a neck-label clamping-device coöperating with said wipers and comprising a lever fulcrumed between its ends on said frame to extend at one end 120
- 120 125. In a labeling-machine, the combination with a supporting-frame having a top-section, of a drive-shaft, a bottle-support, label-wipers, and a neck-label clamping-device coöperating with said wipers and comprising a lever fulcrumed between its ends on said frame to extend at one end 130

over said top-section and operatively connected at its opposite end, for rocking it, with the drive-shaft, a tube supported vertically on said top-section to register with the forward part of said bottle-support and provided with an inwardly projecting stud, a spindle rotatably supported in said tube and containing a spiral-groove with which said stud engages, a link-connection between said lever and the upper end of the spindle, and a clamping-head on the lower end of the spindle.

24. In a labeling-machine, the combination with a supporting-frame having a top-section, of a drive-shaft, a bottle-support, label-wipers, and a neck-label clamping device coöperating with said wipers and comprising a lever fulcrumed between its ends on said frame to extend at one end over said top-section and operatively connected at its opposite end, for rocking it, with the drive-shaft, a tube supported vertically on said top-section to register with the forward part of said bottle-support and provided with an inwardly projecting stud, a spindle rotatably supported in said tube and containing a spiral groove with which said stud engages, a link-connection between said lever and the upper end of the spindle, 30 a clamping-head on the lower end of the spindle, and a guide-shield on said head.

25. In a labeling-machine, the combination with a supporting-frame having a hollow standard and a top-section extending therefrom, of a drive-shaft, a vertically reciprocating rod in said standard operatively engaging the drive-shaft, a bottle-support extending from said standard, label-wipers, and a neck-label clamping device coöperating with said wipers and comprising a lever fulcrumed between its ends on said frame with its rear end engaging said rod and its forward end extending over said top-section and containing a longitudinal slot, a tube adjustably supported vertically on said top-section to register with the forward part of said bottle-support and provided with an inwardly projecting stud, a spindle rotatably supported in said

tube and containing a spiral-groove with which said stud engages, a link adjustably connected with the slotted end of said lever and connected with the upper end of the spindle, and a clamping-head on the lower end of the spindle.

26. In a labeling-machine, the combination with a supporting-frame having a top-section, of a drive-shaft, label-pickers actuated by said drive-shaft, a bottle-support, a supplemental frame adjustably confined on said top-section, a label-magazine depending from said supplemental frame over said bottle-support and into the paths of said pickers and composed of depending arms having inwardly projecting fingers forming a seat for a label-pile, and means for adjusting said arms one with relation to another.

27. In a labeling-machine, the combination with a supporting-frame having a top-section, of a drive-shaft, label-pickers actuated by said drive-shaft, a bottle-support, a bottom-delivery label-magazine depending from said top-section over said bottle-support and into the paths of said pickers, a post on said top-section, a follower-plate in said magazine having a lever extending from it, and a clutch-connection between said lever and post, for the purpose set forth.

28. In a labeling-machine, the combination with a supporting-frame having a top-section, of a drive-shaft, label-pickers actuated by said drive-shaft, a bottle-support, a bottom-delivery label-magazine depending from said top-section over said bottle-support and into the paths of said pickers, a post on said top-section, a head slidingly mounted on said post, a follower-plate in said magazine, and a lever having bent ends with one of said ends pivotally connected with the follower-plate and its other end pivotally connected with said head to clutch the post, for the purpose set forth.

FREDERIC C. WILLIAMS.

In presence of—

A. U. THORIEN,
R. A. SCHAEFER.
